(57) **CLAIM**

The ornamental design for a custom-built-for badge, as shown and described.

DESCRIPTION

FIG. 1 is an oblique view of a custom-built-for badge showing the front of our new design;

FIG. 2 is a front view;

FIG. 3 is a top view;

FIG. 4 is a left view;

FIG. 5 is a right view; and,

FIG. 6 is an oblique view showing the rear of our new design.

The mounting holes and pins shown in broken lines are for illustrative purposes only and form no part of the claimed design.
